UNITED STATES PATENT OFFICE.

WILLIAM O. SWINNERTON AND EGBERT B. SAUNDERS, OF SAN JOSÉ,
CALIFORNIA; SAID SAUNDERS ASSIGNOR TO SAID SWINNERTON.

WINDMILL.

SPECIFICATION forming part of Letters Patent No. 236,277, dated January 4, 1881.

Application filed January 19, 1880.

To all whom it may concern:

Be it known that we, WILLIAM O. SWINNERTON and EGBERT B. SAUNDERS, of San José, county of Santa Clara, and State of California, have invented an Improved Windmill; and we hereby declare the following to be a full, clear, and exact description thereof.

Our invention relates to certain improvements in windmills; and it consists in certain details of construction and combinations of devices, as hereinafter fully described, specifically claimed, and illustrated in the accompanying drawings, making part of this specification, in which—

15 Figure 1 is a perspective view of our mill. Fig. 2 is a side sectional view. Fig. 3 is a top or plan view.

20 A A are the posts forming the base and support of our mill, only the upper parts of which are shown in the present case. These posts are caused to meet at the top, being cut away so as to inclose a pipe or tube, B, of considerable size, which surrounds the pitman or connecting-rod C, and also serves as a pivotal post, 25 about which the upper part of the mill is allowed to turn. We prefer to make this tube of large four-inch gas-pipe, and it extends downward, so as to have its lower end rest upon and be steadied by cross-braces or a plat- 30 form, which is supported between the timbers A at a suitable distance below the top. The timbers A are secured together, preferably, by long bolts which pass through the timbers and are secured by nuts.

35 The frame D, which serves as a support for the wheel and rudder, is strongly fastened together, and the lower cross-timber is pierced so as to allow it to slip down over the tube B, around which it turns loosely. Beneath the 40 upper cross-timber of the frame is a plate of metal, E, which rests upon the top of the pipe and serves as a bearing upon which the whole weight of the mill is supported, and upon which it rotates, the bearing being thus reduced to so small a surface that the mill turns with but little friction, and will thus be affected by very slight movements in the air. This plate and the upper frame-timbers have 45 a hole made through them smaller than the size of the pipe B, so as to admit a short sec-

tion of smaller pipe, which may be screwed in the outer one and project up through the plate and timber to serve as a guide. The pipe also admits the passage of the pump or connecting rod C.

55

The wheel is formed of radial arms F, secured between central flanges, G, and suitably braced and united for strength. The number of arms may be varied, but we have found that about twenty will give a maximum of 60 power without breaking up the current of air too much.

The vanes H of our wheel are formed by the union of two boards, which may be of equal or unequal width, and which meet, either at 65 the central line of the vane or at one side, if preferred, at an obtuse angle, as shown in Fig. 2. Obtuse triangular blocks are secured between the angular sides to strengthen each vane. These vanes are secured to the arms of 70 the wheel so as to stand at an oblique angle with the plane of its face, and it will be seen that the current of air will strike the first portion of the vane at a greater angle than that of the second portion, so that as it is deflected 75 from the first it acts upon the decreased angle of the second portion. Experience proves that this form of vane gives better results than a vane having the same angle of obliquity throughout its entire width.

80

The wheel is mounted upon a crank-shaft, I, which is supported in boxes secured to one side of the frame D, and secured in the present case at a point midway between the top and bottom. A vertical connecting-rod, J, extends 85 from the crank to the horizontal vibrating bar K, and is united to it by a pin. Holes are made along this vibrating bar to receive the pin and allow the rod J to connect with the bar K at different points, so as to vary the 90 length of stroke. The opposite end of the vibrating bar has a cross or T head, the ends of which form journals on which it turns, and as these are considerably separated the vibrating arm K is steadied and side motion is prevented. The pump connecting-rod C, which passes down through the tube B, is attached to the vibrating bar K, which crosses above 95 the tube.

The tail or rudder L is made, preferably, of 100

greater depth vertically than its length, the proportions being about as seven to four. Bars M are bolted to it to strengthen it. The pivotal post N of the rudder is secured to the inner ends of the horizontal strengthening-bars M, and stands at an angle, as shown, its foot being nearer to the frame D than its upper end. By this construction it will be seen that when the rudder is turned out of a plane at right angles with the wheel it will also be raised upward around its oblique axis, so that when released from the power which turned it it will fall back to its normal position by gravitation.

As the wheel-shaft is supported in a line outside of the vertical axis of the mill, it will be seen that the pressure of the wind upon the wheel will have a tendency to turn the mill upon its support; but the action of the wind upon the rudder will also hold the wheel in the wind until it becomes strong, when the rudder will turn and the wheel will approach it until the wheel is caused to stand edge to the wind, and thus its revolution be stopped.

As the rudder will turn obliquely upward it will be seen that when the force of the wind decreases the rudder will fall back toward its normal position. This position is not quite at right angles with the face of the wheel, because the wheel is placed, as before stated, at one side of the vertical axis of the mill. We therefore place the pivotal post N of the rudder at an oblique angle with a vertical plane taken through the axis of the mill, so that the rudder will in quiet weather always stand a little out of a direct line, as shown in Fig. 3. When the wind blows gently it will bring the rudder into a direct line, and the stronger gales will cause the rudder to turn out of a direct line to the opposite side, as before described.

A bar, O, is secured across the frame D, and this limits the movement of the rudder and prevents its striking the wheel in its extreme movements.

A short arm or block, P, is secured to the side of the rudder, and a cord, Q, leads from it, down through the pipe D, to a point within reach of the operator, so that the rudder may be turned and the wheel thrown out of the wind whenever desired.

A weight, R, is fitted to one of the timbers M upon the rudder, and by moving it toward or away from the post N the power needed to

swing the rudder will be increased or diminished.

Having thus described our invention, what we claim as new, and desire to secure by Letters Patent, is—

1. The improvement in windmills consisting of the tube B, extending upward between and supported by the converging frame-posts A, in combination with the frame D, the lower bar of which surrounds the tube, while the upper bar is provided with a bearing-plate which rests upon and is steadied by the tube, substantially as herein described.

2. The wheel-vanes H, each composed of two planes meeting at or near a central line at an obtuse angle, and provided with the triangular supporting-blocks, to which they are secured, as shown, said vanes being secured to the arms F, so that the wind will strike the first portion of the vane at a greater angle than the second, substantially as herein described.

3. The bar K, extending horizontally above the tube B to receive the pump-rod attachment, and having its outer or moving end slotted or perforated to receive the connecting-rod J and adjust the length of the stroke, while its opposite end has a transverse bar or shaft, the ends of which form journals, about which the bar oscillates, and which steady it and prevent side movement, substantially as herein described.

4. A windmill having the wheel-shaft journaled at one side of the vertical axis, and having the tail hinged or pivoted in a line inclined to the perpendicular, said rudder having an adjustable weight R, substantially as and for the purpose herein described.

5. A windmill having its wheel-shaft journaled within the frame D, which turns upon a vertical axis, in combination with the rudder or tail L, so hinged as to be returned to a position nearly in line with or parallel to the wheel-shaft, and the stop or bar O, substantially as herein described.

In witness whereof we have hereunto set our hands this 22d day of December, A. D. 1879.

WILLIAM O. SWINNERTON.
EGBERT B. SAUNDERS.
